UNITED STATES PATENT OFFICE.

WILLIAM H. RITENOUR, OF PITTSBURGH, PENNSYLVANIA.

TWIN-SLUG COMPOSITION.

Application filed February 8, 1923. Serial No. 617,780.

My invention relates to typographical machines of the general construction of the well-known linotype, wherein matrices and spacebands are assembled into a line by the manipulation of the keyboard, the line presented to a mold and a slug cast therefrom, after which the matrices and spacebands are automatically distributed to their various receptacles.

10 The object of my invention is the production of twin-slug composition by means of relatively long, short, and even-length slugs without the division of a word from a left to a right slug.

15 In order to convey a clear understanding of my invention it is necessary to describe the usual trade method of handling twin-slug composition when the desired measure exceeds the maximum capacity of the machine, which capacity is usually 30 picas. Assuming the desired measure to be 40 picas, the usual custom is to compose two 20-pica twin slugs (a left and a right), which are subsequently doubledup to form a composed 25 line of 40 picas. At the point of jointing a word is broken over from the left to the right slug, or a space is employed either at the end of the left slug or at the beginning of the right slug. This method is objectionable because of the difficulty in securing accurate alinement of one column of slugs with its adjoining twin column when the form is locked up, and also because of certain inaccuracies that are inherent in slug 30 composition relative to location of face to body of slug, thereby causing white space to appear between the letters of a word broken over two adjoining slugs.

35 I attain the objects of my invention in connection with any linotype or similar machine by a novel method, illustrated in the accompanying drawings, and in which—

40 Figure 1 is an outline of a printed impression of a line composed in accordance with my invention;

Fig. 2 is similar to Fig. 1, but showing a modified form;

Fig. 3 is similar to Fig. 1, but showing another modified form;

45 Fig. 4 is an outlined printed impression of two lines composed in accordance with my invention;

Fig. 5 is a printed impression of the composition represented in Figs. 1, 2, 3 and 4, 50 showing it in jointed form;

Fig. 6 is a front elevation of a portion

of the machine with my copyboard and indicator applied thereto;

Fig. 7 is an enlarged fragmentary perspective view, taken on the line 23—23, showing the indicator block, the actuating lever and its finger, the indicator lock, and the assembling elevator lever, in inoperative position;

Fig. 8 is similar to Fig. 7 but showing the indicator mechanism in an operative position;

Fig. 9 is similar to Fig. 7 but showing the indicator mechanism in still another position;

Fig. 10 is a detail view of the lift attached to the assembling elevator lever;

Fig. 11 is a fragmentary front view of copyboard, showing the face of indicator block in one of its four positions;

Figs. 12, 13 and 14 are detail views of the faces of the remaining three sides of the indicator block; and

Fig. 15 is a sectional view of copyboard, taken on the line 24—24.

The essence of my invention consists in the composition of twin-slug linotype matter by employing slugs of varying lengths, at the same time eliminating the division of any word from a left to a right slug. To avoid changes in mechanism, this result is attained by oversetting two slugs of even lengths, the overset section (hereinafter designated as "cut-off") being formed by pica-setwise matrices, preferably bearing a distinctive design, whereby the part of the slug to be removed is subsequently readily distinguished. Assuming that a 40-pica line is desired, Fig. 1 shows how it would be composed by employing two 21-pica slugs, 55 the two-pica "cut-off" of the left slug 2 being represented by 1—1, which, when removed before the printing operation, reduces the length of the left slug 2 to the measure of 19 picas. Jointed with its twin right slug 3, which measures 21 picas, the total pica measure is that required for printing purposes: 40 picas.

To produce a type-form containing long and short slugs for the purpose of causing an interlocking or dovetailing arrangement when the slugs are made-up into a form, it is necessary to vary the location of the "cut-off" 1—1 relative to left and right slugs. Fig. 2 shows how this may be accomplished 105 by an overset line bearing the "cut-off" 1—1 on the right slug 3. However, the partic-

ular location of the "cut-off" does not necessarily follow in the alternate order illustrated in Figs. 1 and 2, as will now be explained:

5 In Fig. 3 is shown a twin-slug line bearing a one-pica "cut-off" 1 on the left slug and also a one-pica "cut-off" 1 on the right slug 3, this formation being caused by avoidance of the division of the word 10 "Cologne," it being impossible to compose the whole of said word in the left slug 2 if it were desired to make it a short slug similar to slug 2 of Fig. 1, as would be the 15 regular predetermined order. It would likewise be objectionable, for typographical reasons, to set this particular slug as a long slug, (similar to left slug 2 of Fig. 2). Accordingly, the "cut-off" is divided evenly 20 over the two slugs 2-3 (Fig. 3) and the division of the word "Cologne" is thereby avoided.

It should be particularly noted at this point that the carrying out of the invention may be largely performed by the regular 25 sequence of a short slug and a long slug to form one line, and a long slug and a short slug to form the succeeding line, and so on, as clearly shown in Figs. 1 and 2, such sequence being automatically directed by an 30 indicator later to be described herein. Yet it will be found in practice that to avoid the division of a word over two slugs it will be necessary to interrupt the sequence in still another manner different to the departure 35 just shown by Fig. 3. Thus, it will be occasionally necessary to compose a long slug 2^a and a short slug 3^a to form one line, and likewise a long slug 2^b and a short slug 3^b to form the succeeding line, as illustrated 40 in Fig. 4. For the left slug 2^b of Fig. 4 a short slug would be employed by predetermined order. To do so, however, would involve the division of the word "exceptionally." Accordingly, the "cut-off" is carried 45 to the right slug 3^b and the interlocking feature, heretofore described, momentarily dropped for the sake of avoiding the division of the word "exceptionally."

It will now be apparent that the location 50 of the "cut-off" on twin slugs overset in accordance with my invention depends upon the regular jointing of slugs that may be designated as short left, long right, long left, short right, and so on, until the avoidance 55 of word division requires that this regular order be dropped and the "cut-off" so located that the space 4 may be placed either at the end of the left slug or at the beginning of the right slug. The elimination of 60 word division in twin-slug composition is, I believe, a new feature in the art.

To carry out the objects of the invention 65 the linotype machine is equipped with a rectangular indicator block 5, pivoted with- 65 in a mortise contained in copyboard 6

(Fig. 11), said indicator block bearing upon its longitudinal sides four guides, which are operably exposed in the sequential order illustrated in Figs. 11, 12, 13 and 14. The shaded squares 11 (Figs. 11 and 14) of said 70 guides are printed in red and serve as guides to the operator for the setting of the "cut-off," heretofore described. The remaining squares 12 are printed in black and provide means whereby the operator 75 may enter the number of ems required for any indentation, or series of indentations, in composing copy, all of which will be readily understood by the experienced compositor.

Fig. 7 shows the lever 13, which is attached to the under side of copyboard 6 by a hinge 14, the adjusting screw 15 providing a seat for said lever when in the normal position shown. Pivoted inside a mortise in lever 13 is the indicator operating-finger 16, 80 the pitch of which is adjustable to indicator block 5 by means of the adjusting plate 17. The lift 18 (Figs. 7 and 10) is operably attached to the arm 19 of the well-known assembling elevator lever 20. Raising of the 85 assembling elevator lever 20 to deliver a line a matrices to the casting mechanism causes the lift 18 to elevate the lever 13 and with it the finger 16, which pushes upwardly under the indicator block 5 and thereby exposes the guide to be followed in composing the succeeding slug. Fig. 8 next shows the finger 16 about to be pushed away from the side of the indicator block 5, at which position the weight lock 21 is at its uppermost 90 elevation. Fig. 9 next shows the finger 16 clear of operative engagement with indicator block 5 and the weight lock 21 again resting in normal position. The descent of the assembling elevator 22 (Fig. 6) causes 95 the lever 13 to drop into normal position as shown in Fig. 7, during which operation the indicator block 5 is held against movement by the back-leash of finger 16 by the weight 100 of the lock 21.

When required to change the predetermined order governing the location of the "cut-off", as controlled by the sequential exposure of the guides heretofore described, the operator merely turns the indicator block 115 5 by hand to coincide with the altered course made necessary in avoiding word division.

A copy-follower 7 (Fig. 11), tied by laces 8 to weights 9 (Fig. 15), provides a simple means whereby the operator may follow 120 complicated copy, line by line, even though the copy may be furnished in bulky form. The weights 9 are enclosed in square tubes 10, thereby rendering the entire copyboard 125 self-contained and instantly removable from the machine without the disengagement or displacement of any parts.

Manifestly many modifications may be developed that might accomplish, in less preferred form, the ends attained in this in- 130

vention, and yet will be comprehended in its scope. Since the combination of an operable indicator and an actuating device controlled by the periodical operation of the machine is new in the art, I claim the same broadly and in any mechanical equivalent.

I claim:

1. In combination, the assembling mechanism of a typographical machine, means cooperating with said mechanism, and means adapted to be actuated by the last mentioned means to automatically signal a predetermined order of twin-slug composition.

2. In combination, the assembling mechanism of a typographical machine, means cooperating with said mechanism, means to automatically signal a predetermined order of twin-slug composition, and means to indicate the location of overset sections, substantially as described.

3. In combination, the assembling mechanism of a typographical machine, means cooperating with said mechanism, means to automatically signal a predetermined order of twin-slug composition, and means to separately indicate the "left" slug and the "right" slug during the composition of a twin-slug line of typographical matter, substantially as described.

4. In combination, the assembling mechanism of a typographical machine, means cooperating with said mechanism, means to automatically signal a predetermined order of twin-slug composition, and means to separately indicate the "long" slug and the "short" slug during the composition of a twin-slug line of typographical matter, substantially as described.

5. In combination, the assembling mecha-

nism of a typographical machine, means whereby the assembling elevator lever arm 19 cooperates with means to automatically signal a predetermined order of twin-slug composition, and means to lock the signaling means against displacement until actuated by the operating means or by hand.

6. In combination, the assembling mechanism of a typographical machine, means cooperating with said mechanism, means to automatically signal a predetermined order of twin-slug composition, means to lock the signaling means against displacement, and means to automatically release said locking means simultaneously with the operation of the signaling means.

7. An attachment for typographical machines comprising a copyboard containing in its front face an operable indicator bearing a series of twin-slug guides, means to actuate said indicator by engagement with a periodically-moved organ, and means to lock and unlock said indicator in relatively inoperative and operative positions.

8. The herein-described method of twin-slug composition, consisting of oversetting two slugs of even lengths to form one line of reading matter, the overset sections being formed in typographical units and bearing no reading matter characters.

9. The herein described method of composing twin-slug matter, consisting of oversetting two slugs of even lengths to form one line of reading matter, the overset sections as specified in claim 8 being allocated to either or both of said two slugs whereby the division of a word from a left to a right slug is avoided.

WILLIAM H. RITENOUR.
